UNITED STATES PATENT OFFICE.

GEORGE BATES THAYER AND ERSKINE D. WHEELER, OF BENTON HARBOR, MICHIGAN.

MECHANISM FOR WIRING BASKETS.

SPECIFICATION forming part of Letters Patent No. 573,311, dated December 15, 1896.

Application filed October 11, 1895. Serial No. 565,366. (No model.)

To all whom it may concern:

Be it known that we, GEORGE BATES THAYER and ERSKINE D. WHEELER, citizens of the United States, residing at Benton Harbor, in the county of Berrien and State of Michigan, have invented certain new and useful Improvements in Mechanism for Wiring Baskets; and we do hereby declare the following to be a full, clear, and exact description of the invention, such as will enable others skilled in the art to which it appertains to make and use the same.

This invention relates to improvements, as hereinafter set forth, in mechanism for wiring 15 or stapling fruit and other baskets or boxes.

In the accompanying drawings we have represented our improvements as adapted to the wiring of baskets having a splint-body portion, a wooden bottom, and top and bottom 20 strengthening bands or hoops, though the improvements are equally well adapted for wiring baskets or boxes of other character.

In the accompanying drawings, Figure 1 represents a perspective view showing our 25 improvements in position on a stapling-machine. Fig. 2 represents a front elevation of the stationary or non-rotatable cross-head and parts carried thereby. Fig. 3 represents a side elevation thereof. Fig. 4 represents 30 a side elevation of the rotary-cross-head on which the basket-form is supported and slides. Fig. 5 is a top plan view of Fig. 4. Fig. 6 represents a perspective view, partly broken away, of a portion of the basket support or form mounted on the rotary supporting cross-head. Fig. 7 represents a longitudinal sectional view of the basket-form, its 35 supporting cross-head, and the staple-clenching devices assembled. Fig. 8 represents a rear view of the basket-form and its adjustable supporting cross-head. Figs. 9 and 10 are detail views hereinafter described.

1 represents the base, 2 the uprights, 3 the top piece or table, 4 the wire-reel, 5 the staple-inserting mechanism, and 6 the treadle 45 and 7 the plunger of a staple inserting or driving machine, which may be of any approved construction.

8 represents a pair of rods having slide-bearing in lugs 9 on the uprights 2 and angularly connecting at their front ends with and

so as to support the stationary or non-rotatable cross-head carrying the staple-clenching anvil, to be presently described, and present the basket-hoops on a level with the table 3. 55 10 represents a lever having a bifurcated or forked lower portion 11 to straddle the base 1, said forked lower portion having pivotal bearing-support in ears 12, extending from the base 1. 60

13 represents a rotatable ball or wheel on the top of the lever 10. 14 represents a cord connected at its front or upper end, as at 15, with said lever, and from thence extending over a grooved or other pulley 16, supported 65 on the front upright 2, and from thence extending down to and connected at its lower end, as at 17, with another treadle 18. The function of this lever 10 is to hold the basket 19 and its form in position during the operations of inserting and clenching the staples, thereby dispensing with the necessity of holding the basket and form to position by hand, and leaving the hands of the operator free to slide the basket and form, as required, and 70 also to attend to the other parts of the mechanism. It will readily be observed on reference to Fig. 1 that by foot-pressure on the treadle 18 the lever 10 will be rocked on its pivots to bring the rotatable ball 13 against 75 the bottom of the basket and thereby hold said basket and the basket-form to position, while by releasing or loosening the foot-pressure on said treadle said basket and form may be readily moved or the basket removed, 80 85 as desired.

20 represents the basket-form on which the basket is built up and held while the bottom and hoops are stapled to the body portion. Such a basket, as shown in the drawings, on 90 which our apparatus is especially designed to operate, though the apparatus is equally well adapted for use on other baskets and the like, consists of a splint-body portion 21, a wooden bottom 22, bottom hoop 23, and a pair of top 95 hoops 24. In constructing the basket of this character the wooden bottom is placed against the front portion of the form 20 and held in such position by the pressure against said bottom of the rotary ball 13 of the lever 10, 100 which, as before stated, is accomplished by pressure on the treadle 18. A hoop similar

to that marked 24 is then placed around the other or inner edge of the form 20. The splint body 21 is then placed around the basket-form with its top portion resting on the said inner 5 hoop and its bottom portion resting on the edges of the wooden bottom. The bottom hoop 23 and the outer top hoop 24 are then placed in position, as shown in Fig. 1. By this operation it will be readily apparent that the 10 splint-body portion of the basket is gripped and clamped at its bottom between the edges of the bottom and the bottom hoop and at its top between the inner and outer hoops. In this position the several parts of the basket 15 are in readiness for being wired or stapled together by the mechanism to be presently described in order to produce a complete basket ready for use.

The basket-form 20 is of a shape corresponding 20 with the shape of the basket to be produced. In the drawings it is shown as of substantially rectangular forwardly-tapering form, (see Fig. 7,) the tapering portion 25 corresponding with the lower portion of the basket. The inner or widest portion of the form 20 has solid walls and has a circumferential 25 open groove or slot 26 and bracing corner-strips 27, lugs 28 extending inwardly from each end for the purpose of releasing the spring-pawl, to be presently described. The tapering forward portion 25 of the form (see Figs. 6 and 7) may be of skeleton formation.

29 represents the non-rotatable cross-head, which has bearing-support on the frame by 35 means of the rods 8, which latter have limited reciprocal longitudinal movement in the lugs 9, so as to admit of the basket and its form being presented at both the top and bottom portions thereof to the stapling mechanism.

30 represents a ring removably secured by screws 31 to a series of studs or short rods 32, extending inwardly from the cross-head 29. 33 represents a notch or recess formed in the 45 inner edge of said ring to receive alternately the spring-pawls according to the position of the basket-form and basket.

34 represents an inwardly-extending centrally-bored boss of the cross-head 29. In 50 the upper portion of this boss is journaled a roller 35, which as the basket-form 20 is turned for stapling runs in contact with the iron frame, (see Figs. 7 and 9,) thus greatly relieving friction and facilitating turning the frame. The said roller has a journal-pin 55 on one side only and is held in place by the ring 30.

36 represents a rigid clenched-block or anvil 60 extending upwardly from the boss 34, as shown in Fig. 7. This clenched-block or anvil in use extends through the groove 26 in the basket-form to receive the impact of and clenched the staple-legs. The block 36 runs in the slot 26, Figs. 6 and 10, as the basket-form rotates, 65 but does not come in contact with the strips 27, since the latter are located eccentrically

or at the convex corners of the form, Fig. 10, beyond the radius of said block.

37 38 represent a pair of longitudinal division-plates in the basket-form 20, constituting 70 a longitudinal way 39 to receive a rotary cross-head 40 and admit of the longitudinal reciprocal travel on said cross-head 40 of said basket-form. This cross-head 40 has a central bore 41 to receive a bolt or pin 42, on which said cross-head has rotary bearing and revolves when the basket-form is turned end-wise and from one side to the other, said pin or bolt also serving to connect the cross-heads 29 and 40 together, as shown in Fig. 7. 80

43 represents a hub on which the boss 34 has bearing.

The cross-head 40 has a pair of upper and a pair of lower jaws 44 45, within or between which the basket-form has slide-bearing, the 85 edges of the division-plates 37 38 having bearing on the horizontal portion of the ways formed by said jaws, as clearly shown in Fig. 6. 46 47 represent flat horizontal portions of said jaws. 90

48 49 represent a pair of spring-projected pawls pivoted at 50 51 in side slots in the rotary cross-head, 52 representing the springs engaging said pawls.

The parts being assembled as indicated in 95 Fig. 7 and positioned on the wiring-machine as indicated in Fig. 1, the pawl 48 will be in engagement with the notch 33 in the ring 30, which engagement of pawl with said ring holds the form from oscillating or turning 100 while being slid on the rotary cross-head to wire the sides of the basket. The basket is then built on the form 20, as previously described. The wiring mechanism is then actuated and the form with the basket material 105 thereon is then slid across the rotary head, the staples being driven in the edges of the bottom during the horizontal movement of the basket-form, as will be readily understood, so as to wire the bottom hoop, the bottom of the splint body, and the wooden bottom together. When one side of the basket 110 has thus been wired, the end of the basket-form 20 has reached the rotary cross-head 40. Thereupon the adjacent end lug 28 strikes 115 against the pawl 48, and, forcing said pawl inward, releases said pawl from the notch 33 in the ring 30. The basket-form is then raised by roller 35 and turned and the stapling of the end of the basket is accomplished. 120

Then the roller contacts with the next corner-strip and again raises the form, which is then turned over to bring the other side of the basket-form and basket uppermost, the rotary cross-head rotating with the form, as will 125 be well understood. As the basket-form is thus turned over the pawl 49 is brought into engagement with the ring-notch 33 to again hold the form from oscillation. The rods 8 are susceptible of longitudinal movement to 130 admit of the form being moved either inward or outward, so as to bring the basket under

the staple-inserting device to secure the stapling of either the top or bottom of the basket, as desired, nuts on said rods serving to limit the reciprocal movements of said rods to the appropriate distances to insure the form moving only the requisite distances to bring the top and the bottom of the basket under the stapling mechanism.

Having thus described our invention, what we claim is—

1. A device for forming and wiring the component parts of a splint or similar basket, consisting of a staple-driving machine, a pair of reciprocal rods having bearing on the frame 15 of said staple-driving machine, a cross-head rigidly secured to said rods, a staple-clenching anvil carried by said cross-head, a cross-head rotatably connected with said rigid cross-head, and a basket-form having slide-bearing on said rotary cross-head, substantially as and for the purpose set forth.

2. A device for forming and wiring the component parts of a splint or other basket, consisting of a staple-driving machine, a pair of rods having limited reciprocal bearing on the frame of said machine, a cross-head rigidly secured to said rods, a staple-clenching anvil carried by said cross-head, a cross-head rotatably connected with said rigid cross-head, 30 a lever having pivotal bearing on the staple-driving machine and a ball or wheel having rotatable bearing on the top of said lever adapted to bear at its upper portion against the bottom of the basket and hold said basket and the basket-form in position with freedom of reciprocal movement, a treadle pivoted on the frame of the said machine, and means, as a cord, connecting said lever and treadle, substantially as and for the purpose 40 set forth.

3. In a machine for wiring splint and other baskets, a staple-driving machine, a cross-head reciprocally mounted thereon, a staple-

clenching anvil and a roller carried by said cross-head, a cross-head rotatably connected 45 with said reciprocal cross-head and having upper and lower horizontal grooves in its front portion, a basket-form having upper and lower, inner, division-plates each having slide-bearing in said grooves, and an open 50 slot around the inner edge and corner-strips extending transversely across said slot, substantially as and for the purpose set forth.

4. The combination with a staple-driver, of a cross-head having non-rotatable support, a 55 staple-clenching anvil carried by and extending beyond the periphery of said cross-head, a roller and a notched ring carried by said cross-head, a cross-head loosely connected with said non-rotatable cross-head and having rotatable bearing on said connection, spring-pawls having pivotal bearing in recesses in the sides of said rotary cross-head, a basket-form having slide-bearing on said rotary cross-head, an open slot around its inner edge transverse corner-strips and a lug extending inwardly from each end of said basket-form, substantially as and for the purpose set forth.

5. The combination with a staple-driver of 70 a horizontally reciprocal cross-head, a staple-clench carried by said cross-head, a rotary cross-head loosely connected with said reciprocal cross-head, a basket-form having slide-bearing on and adapted to rotate in unison 75 with said rotary cross-head and having a circumferentially-slotted portion to receive the staple-clench, substantially as and for the purpose set forth.

In testimony whereof we affix our signatures in presence of two witnesses.

GEORGE BATES THAYER.
ERSKINE D. WHEELER.
